UNITED STATES PATENT OFFICE

127,956

DESIGN FOR AN EMBROIDERED FABRIC

Sam Landau, New York, N. Y.

Application May 5, 1941, Serial No. 100,774

Term of patent 3½ years

To all whom it may concern:

Be it known that I, Sam Landau, a citizen of the United States, residing at Manhattan, in the county of New York and State of New York, have invented a new, original, and ornamental Design for an Embroidered Fabric, of which the following is a specification, reference being had to the accompanying drawing, forming part thereof, wherein

The figure is a plan view of an embroidered fabric, showing my new design.

I claim:

The ornamental design for an embroidered fabric, substantially as shown.

SAM LANDAU.
